CARBURETOR

Original Filed June 11, 1929

UNITED STATES PATENT OFFICE

MICHAEL A. S. LAVIGNE, OF WORCESTER, MASSACHUSETTS

CARBURETOR

Application filed June 11, 1929, Serial No. 370,397. Renewed November 17, 1930.

This invention relates to carburetors for internal combustion engines, and pertains particularly to features of construction whereby efficient carburetion and control of carburetion is effected.

One feature of the invention is the relation between the float chamber and centrally located concentric baffles, which provide the plurality of concentric air passages upwardly through the body of the carburetor casing. This feature includes also the particular construction whereby the pipe connection from the float chamber to a central fuel jet provides the supporting strength for holding the central baffles in position. Another related feature is the shape of one of the upright baffles and particularly the upper end of one of them which is curved over the central-most air passage.

Another feature of the invention pertains to the particular shape of the interior of the top dome or cover, and to a peculiarly shaped deflecting baffle which stands in the path of the fuel mixture after it leaves the point of initial carburetion.

Another feature of the invention relates to the control of the fresh air and pertains to a particular automatic choke device which is positioned in the carburetor intake pipe. This device is peculiar in that a spring-held valve plate stands in an open position, normally, when the carburetor or its engine is idle, after which the valve is closed when the engine initially fires and at which time the valve constitutes a positive choke. The device is further peculiar in that it is freely yieldable to a wide open position when the engine speeds up, and in this latter position, the valve plate has moved to a position on the opposite side of its seat from that position where the plate stood when the carburetor was not in use.

The above and other additional features and advantages will be described and claimed in the following specification and claims, and illustrated in the accompanying drawing, in which:—

Figure 1 represents a vertical section through the center of the carburetor and showing the engine end at the upper portion

and the fresh air intake with the automatic choke device therein at the lower portion;

Figure 2 represents a sectional view taken through the top manifold cover and on the line 2—2 of Figure 1; looking downwardly;

Figure 3 is a sectional view on the line 3—3 of Figure 1, taken through the main casing and showing the relative position of the air intake passages with respect to the casing wall; and

Figure 4 is a view of a modification of the automatic fresh air intake valve, which is peculiar in that the valve seat is formed in the intake pipe.

Like reference characters identify like parts in the several figures of the drawing.

Referring in detail to the drawing, 1 is the main casing wall which encloses the float chamber and other parts of the mixing apparatus of the carburetor. 2 indicates the cover, which is adapted to be securely fastened to the casing 1, and which has an annular flat plate portion 2^a, which is adapted to tightly close the upper side of the float chamber. At the extreme upper left hand portion of Figure 1 is the discharge opening 3 which is connected to the engine intake manifold and is adapted to be controlled by the throttle valve 4, mounted on the shaft 5. At the lower end of the carburetor is the fresh air intake pipe 6, which normally receives fresh heated air from the usual stove connected to the exhaust manifold of an engine.

The main bowl or casing 1 is peculiar in that it is cast in one piece and also has the particular feature now to be described. Immediately beneath the floor of the bowl and in line with the bore of the intake pipe 6, there is an enlarged space 7, through which the incoming air is led upwardly into the body of the carburetor.

8 indicates the annular float chamber, the outer wall of which is the casing 1, and the inner wall of which is provided by a central upright wall 9, which extends from the floor of the chamber to the flat plate portion 2^a, and joins the plate portion with a tight joint as indicated at 9^a. On the central side of the wall 9 is a second upright wall 10, and im-

mediately at the central portion of the casing is the upright fuel pipe 11, which terminates at its upper end in the jet opening 11^a. In Figure 1, 11^a is illustrated as formed separately from 11 and screw-threaded to it. It is obvious that jet openings of different sizes may be substituted where the jet orifice portion is thus removable. Passageways for incoming air are provided at 12 between the 10 walls 9 and 10, and at 13 between the walls 10 and 11, respectively. The upper end of the wall 10 is extended above the level of the jet opening and is turned inwardly and centrally, providing the inwardly projecting flange 15 at 10^a.

Fuel from the float chamber 8 reaches the central fuel pipe and its interior bore 14 by passing through a supporting pipe 15, which bridges the central space from one side of the 20 annular float chamber to the opposite side. The pipe 15 has a central bore 16, through which the fuel flows. The pipe 15 serves also as supporting means for the walls 10 and 11, and insures rigidity of these parts by being 25 anchored at both ends to the floor of the carburetor bowl and by being cast in one piece with the bowl and with the parts which it thus supports. One or more spiral baffles 17 are positioned in the air space 13, between the 30 walls 10 and 11, and serve to provide the air with a swirling helical movement twisting upwardly through the passageway 13 and over the end of the jet opening at 11^a. One such spiral baffle 17 is shown in Figure 1 as 35 bridging the space between the walls 10 and 11, and in Figure 3 two baffles are shown similar to a double helix one on each side of the center wall 11.

A control valve terminating in a needle 40 point is provided by a rod 18, which projects downwardly through the upper central point of the cover member 2, and which may be adjusted to vary the flow of liquid from the opening at 11^a.

The supply of fuel to the float chamber is 45 led in through a supply pipe 19, which is connected to the cover member 2. A needle valve 20 points upwardly and controls the downward flow under the action of an annular float member 21, which is hinged at 22 and which carries an arm 23 to engage with the needle valve 20. In Figure 1, the float is shown in its upper position with the arm 23 50 raised against the lower end of the needle 20, thus closing the needle valve against additional intake of liquid fuel.

The walls of the dome-like cover member 2 are peculiar in that they are spaced outwardly away from the central opening 9^a and there is thus the beforementioned flat cover plate portion 2^a, the under surface of which constitutes the roof for the float chamber and the upper surface of which 55 constitutes the floor of the dome portion.

Directly across the path of the fuel mixture within the dome, there is a peculiarly shaped deflecting baffle 24, which starts at the plate 2^a and is curved upwardly on the side next to the outlet opening 3 and away from that 70 opening. It thus extends as an overhanging curved wall above the path of the upwardly moving fuel mixture. This deflecting baffle 24 begins at the opposite side walls of the opening 9^a and slopes abruptly upward from 75 the points 24^a to the uppermost point 24^b. The interior of the dome of the casing cover is curved and the edge of the baffle 24 is correspondingly curved and is spaced from the inner surface of the dome. 80

Directly opposite to the deflecting baffle 24 is an upright vane or fin 25, which extends as a rib from the upper part of the dome to the floor thereof at that portion of the casing directly adjacent the needle valve 20. 85 The opening for the needle valve 20 is formed in the enlargement of the cover wall, which results in the projecting fin 25.

In the upward movement of incoming air, after it has been mixed with the fuel, the resultant mixture is drawn upwardly striking the under face of the baffle 24, and rebounding to the opposite wall of the dome, where it is divided into two main streams by the projecting fin 25. This construction has 90 resulted in unusual efficiency by reason of the tumbling movement given the gases and the tortuous passage through which they pass. 95

Referring in detail to the automatic fresh air control valve, in Figure 1, there is shown 100 a sleeve 26, which has been inserted into the pipe 6 and within which it has a relatively close fit, so as to prevent the passage of air between the sleeve and the pipe. A set screw 27 holds the sleeve in position. On 105 the inner surface of the sleeve is an inwardly projecting ridge which may be considered the equivalent of a door frame and which is indicated at 28. A disc-like valve 29 is so mounted as to substantially close the opening 110 of the door frame under certain conditions and must be free to move from one side of the frame to the other. The mounting of this valve 29 includes a slidable rod 30, which is journaled in cross braces 31 and 32, 115 which latter extend across the bore of the sleeve 26 and are fixed with respect to the sleeve. A spring 33, encircling the rod 30, abuts the valve disc 29 on the carburetor side, and normally yieldably holds the valve 120 spaced from the part 28 and on the intake side thereof. A relatively shorter spring 34 prevents the disc 29 from moving too far away from the part 28 on the intake side and assists in thrusting the valve to the closed position when the suction from the engine or carburetor tends to draw the valve engine- 125 ward. As shown, the spring 33 is relatively long, as compared to the spring 34, and in- 130

cludes a larger number of turns. This device is peculiar because it is set to operate in the following manner. When the carburetor is drawn upon by relatively slow movement of the engine, it is desirable that there be some freedom of movement for air so as to avoid the dragging action of a vacuum, and hence the valve disc 29 is held slightly open. Such a condition exists at the time that the 10 engine is being turned by hand or relatively slowly under the first influence of a starter.

As soon as the initial firing has taken place, in order to prevent the engine from dying and in order to make the mixture as 15 rich as possible, in other words to choke the carburetor, the plate 29 is sucked inwardly to a position substantially in line with the part 28, and thus the door is closed and the mixture becomes relatively rich.

20 As the engine speeds up, it provides a strong suction sufficient to draw the valve wide open on the carburetor side of the part 28, and thus the action is automatic.

A modified construction of the automatic air control is shown in Figure 4, in which the rod 30 has its opposite ends journaled in cross pins 35, which are extended through the intake pipe and fastened by cotter pins or other locking pins 36. In this arrangement, a cam 37 operates against the intake face side of the valve disc, and under the influence of some connection which may be controlled from the dash or from the throttle control. For this connection, the cam is 35 mounted on a pin 38, which is journaled in the intake pipe 6, and is subject to the control of a lever 39, which may be connected to the throttle lever of the automobile or other engine on which this carburetor is mounted.

40 I claim:

1. In a carburetor, a main outer casing, the wall of which constitutes the outer wall of a float chamber, an upright fuel pipe positioned centrally within said chamber and having a 45 jet opening at its upper end, a plurality of concentric upright walls between the casing wall and said pipe and spaced apart and providing a plurality of concentric air passages between said fuel pipe and said float chamber, the upper end of the wall next adjacent said fuel pipe extending upwardly and projecting centrally over the air passage about the fuel pipe and terminating in a reduced opening above and spaced from the jet opening, and a spirally extending baffle located in 50 the air passage next adjacent the central fuel pipe whereby air moving upwardly passes over the jet opening with a revolving motion.

2. In a carburetor, a main outer casing, the 55 wall of which constitutes the outer wall of a float chamber, an upright fuel pipe positioned centrally within said chamber and having a jet opening at its upper end, a plurality of concentric upright walls between the casing 60 wall and said pipe and spaced apart and pro-

viding a plurality of concentric air passages between said fuel pipe and said float chamber, the upper end of the wall next adjacent said fuel pipe extending upwardly and projecting centrally over the air passage about the fuel pipe and terminating in a reduced opening above and spaced from the jet opening, and a spirally extending baffle located in the air passage next adjacent the central fuel pipe whereby air moving upwardly 70 passes over the jet opening with a revolving motion, and bridging the space between the walls of said air passage.

3. In a carburetor having a casing providing a float chamber and fuel jet opening 80 and an air intake passage positioned centrally with respect thereto, a cover having a lower annular plate closing said float chamber and providing a central passageway for the fuel mixture, said passageway extending 85 first upwardly and thence laterally to a discharge opening and providing a bend in the inner upper central portion of said cover, the inner wall of said cover above said annular plate extending as an enlarged dome, the 90 lower edge of the wall of which is spaced outwardly from the central edge of said plate, and a deflecting baffle located within said cover and extending upwardly from the central edge of said plate and curved corresponding to the curvature of the edge of the plate.

4. In a carburetor having a casing providing a float chamber and fuel jet opening 100 and an air intake passage positioned centrally with respect thereto, a cover having a lower annular plate closing said float chamber and providing a central passageway for the fuel mixture, said passageway extending first upwardly and thence laterally to a discharge opening and providing a bend in the inner 105 upper central portion of said cover, the inner wall of said cover above said annular plate extending as an enlarged dome, the lower edge of the wall of which is spaced outwardly from the central edge of said plate, and a 110 deflecting baffle located within said cover and on the discharge side of said central passageway and extending upwardly from the central edge of said plate on one side of the central opening and thence curved away from 115 the discharge opening and terminating with an upper edge spaced from the inner surface of the dome.

5. In a carburetor having a casing providing a float chamber and fuel jet opening 120 and an air intake passage positioned centrally with respect thereto, a cover having a lower annular plate closing said float chamber and providing a central passageway for the fuel mixture, said passageway extending 125 first upwardly and thence laterally to a discharge opening and providing a bend in the inner upper central portion of said cover, the inner wall of said cover above said annular plate extending as an enlarged dome, the 130

lower edge of the wall of which is spaced outwardly from the central edge of said plate, and a deflecting baffle located within said cover and on the discharge side of said central passageway and extending upwardly from the central edge of said plate on one side of the central opening and thence curved away from the discharge opening and terminating with an upper edge spaced from the inner surface of the dome and conforming to the curve of the inner surface thereof, the opposite sides of said deflecting baffle being located respectively on the opposite sides of said central passageway.

15 In testimony whereof I affix my signature.
MIKE A. S. LAVIGNE.
